(57) **CLAIM**

We claim the ornamental design for a traction motor case, as shown and described.

DESCRIPTION

FIG. 1 is a front perspective view of a traction motor case according to our new design;

FIG. 2 is a rear perspective view thereof;

FIG. 3 is a front view thereof;

FIG. 4 is a rear side view thereof;

FIG. 5 is a right side view thereof;

FIG. 6 is a left view thereof;

FIG. 7 is a top view thereof;

FIG. 8 is a bottom view thereof; and,

FIG. 9 is a perspective view of the traction motor case on a motorcycle.

The broken lines in FIGS. 1-8 illustrate portions of the traction motor case that form no part of the claimed design. The broken lines used in FIG. 9 are for the purpose of illustrating environment of the traction motor case and form no part of the claimed design.

1 Claim, 8 Drawing Sheets
